UNITED STATES PATENT OFFICE.

ALFRED H. SMITH, OF CHAPPAQUA, NEW YORK.

COMPARTMENT FREIGHT CAR.

Application filed December 21, 1921. Serial No. 524,032.

To all whom it may concern:

Be it known that I, ALFRED H. SMITH, a citizen of the United States, and residing at Chappaqua, in the county of Westchester 5 and State of New York, have invented certain new and useful Improvements in Compartment Freight Cars, of which the following is a specification.

It is now the practice to ship less than 10 car load lots in what are known as containers, and a plurality of such containers are placed on the platform of a single carrier, so that one container may be removed 15 from the carrier at an intermediate station without impairing the stability of the other containers on the carrier.

It has also been the practice to provide 20 these containers with wall braces which extend from the top to the bottom of the container.

The object of my invention is to provide 25 on the top of the side walls, or bulkheads, of the carrier, means adapted to engage such wall braces, thereby holding the containers securely on the carrier and preventing them 30 from rocking and shifting on the carrier.

A further object of my invention is to so 35 mount these securing means, that when in inoperative position they are swung back outside of the vertical plane of the inner face 40 of the car's side walls.

My invention consists of a combination of 45 a carrier having vertically disposed walls, bulkheads adapted to receive containers between them, and gravity abutments mounted on said bulkheads, and adapted to be swung into engagement with the containers to space the containers and hold them against rocking and shifting on the carrier.

In the drawings:

Figure 1 is a side elevation of a carrier and two containers, parts being broken away, and parts in section,

Fig. 2 is a detail vertical section on the 45 line 2—2, Figure 1, and

Fig. 3 is a top plan view of Figure 1, parts being broken away.

The reference numeral 1 designates the 50 platform of the carrier, and the reference numeral 2 designates the side wall of the carrier, which wall is provided at its top with the usual angle iron 3.

In the embodiment shown, 4 is a plate riveted to the top of the angle iron 3, said plate having its ends 5 deflected at an angle 55 from the main body of the plate.

The bearings 6 of the deflected end portions of the plate 4, are disposed at an angle to the transverse axis of the carrier as clearly shown in Fig. 3. A stub shaft 7 is mounted 60 in said bearing 6, and secured therein by means of the pin 8. On the other end of the stubshaft 7 is rigidly affixed a cam abutment 9, the engaging face of which is beveled as clearly shown in Fig. 3. The containers 10 65 are adapted to be loaded on a carrier, and are provided with wall braces 11 which extend vertically of the containers from top to bottom thereof. When the containers are in position on the carrier, the cams 9 are thrown 70 over against the wall braces 11 as shown in Fig. 3, and these cams are free to be jolted downwardly into their snug engagement with the braces of the containers, thereby holding the containers securely on the carrier 75 against rocking and shifting.

Said bulkheads 12 are secured on the platform of the carrier at intervals throughout the length of the car, and extend transversely thereof from side wall to side wall, but terminating short of the top edge of the side walls of the carriers and adapted to be engaged by the bottom portion of the containers, as illustrated in Fig. 1, in order to more readily position the containers on the 85 carrier between said bulkheads 12 and side walls.

The walls of the containers are beveled inwardly at the bottom as at 13 (see Fig. 1), which bevel engages the bulkhead as the 90 container is being lowered into position, and directs the container to its proper position on the platform.

Changes may be made in the details of construction without departing from the 95 scope of the appended claims.

What I claim is:

1. The combination with a carrier having vertically disposed bulkheads adapted to receive containers between them, of gravity 100 cam abutments adapted to engage the containers to space them and hold them from shifting or rocking on the carrier.

2. The combination of a carrier having vertically disposed bulkheads, containers 105 mounted on the carrier back of said bulkheads, said containers having vertically disposed wall braces, of gravity cam abutments and adapted to engage the wall braces of the containers to space the containers and hold 110 them from shifting and rocking on the carrier.

3. The combination with a carrier having side and end walls projecting a material distance above the platform of the carrier, of bulkheads on the platform extending from side to side of the carrier and terminating short of the top of the side walls, of containers adapted to be placed between said walls and between said bulkheads, said containers having their walls beveled inwardly at the bottom, which beveled edges are adapted to engage the bulkheads and guide the containers into proper position.
4. The combination with a carrier having side and end walls projecting a material distance above the platform of the carrier, and functioning as bulkheads, containers adapted to be positioned between said walls, wall braces secured to said containers, and abutments pivotally mounted on the top of said side walls of the carrier and adapted to engage the said wall braces above the top of the side walls of the carrier to hold the containers against shifting and rocking on the platform of the carrier.
5. The combination with a carrier having

side and end walls projecting a material distance above the platform of the carrier, of containers adapted to be loaded on said carrier and abutments adapted to engage the containers and hold them against shifting and rocking on the platform; said abutments each comprising a shaft journaled on the top of the side wall at an angle less than a right angle to the side wall of the car, a cam fixedly secured to one end of said shaft, whereby the cam may be positioned outside of the plane of the inner face of the side wall when in inoperative position.

6. The combination with a carrier having side and end walls projecting a material distance above the platform of the carrier, and functioning as bulkheads, containers adapted to be positioned between said walls, abutments secured to said containers, and abutments pivotally mounted on the top of said walls and adapted to engage the abutments on the containers above the top of said walls to hold the containers against shifting and rocking on the platform of the carrier.

In testimony whereof I affix my signature.

ALFRED H. SMITH.
